UNITED STATES PATENT OFFICE.

VICTOR BERNSTEIN, OF BROOKLYN, NEW YORK.

DESIGN FOR A DOLL.

55,841.

Specification for Design.

Patented July 20, 1920.

Application filed December 20, 1919. Serial No. 346,391. Term of patent 3½ years.

To all whom it may concern:

Be it known that I, VICTOR BERNSTEIN, a citizen of the United States, residing in the city of New York, borough of Brooklyn, county of Kings, and State of New York, have invented a new, original, and ornamental Design for Dolls, of which the following is a specification, reference being had to the accompanying drawings, forming part thereof.

Drawings.

Fig. 2 is a side view of the same.

I claim:

The ornamental design for a doll, as shown.

VICTOR BERNSTEIN.
